RHEOSTAT SWITCH

Hugh W. Batcheller, Newton, Mass., assignor to
Standard Mfg. Co., Worcester, Mass., a corpora-
tion of Massachusetts

Application June 5, 1940, Serial No. 338,857

4 Claims. (Cl. 200—11)

This invention relates to a rheostat switch of the type adapted for use in low-voltage circuits such as are employed in automobile lights and electrical accessories.

It is an object of the invention to provide a fused rheostat switch which is compact in structure, reliable in operation, and adapted for long wear.

For a more complete understanding of the invention, reference may be had to the following description thereof and to the drawing of which

Figure 1 is a perspective view of the several parts of a switch embodying the invention.

Figure 2 is a side elevation of the assembled switch.

Figure 3 is a bottom plan view of the main portion of the switch.

Figure 4 is a section on the line 4—4 of Figure 2.

Figure 5 is a section on the line 5—5 of Figure 2.

Figure 6 is a section on the line 6—6 of Figure 5.

As shown in Figure 1, the switch may comprise a housing consisting of a rectangular metal shell 10 which fits upon a base plate 12, the shell 10 being provided with a suitable number of ears 14 which are bent into pockets 16 in the side edges of the plate 12 so as to hold the shell and plate assembled. Slidable above the upper face of the plate 12 is a rectangular slide 20 which fits slidably between the side walls of the shell 10 and which may have longitudinal runners 21 to bear against the under face of the top of the shell 10. The slide is operated by means of a stem 22 which projects through the bore of a neck element 24 at one end of the shell 10, this neck element being externally screw-threaded to receive a pair of nuts 26 by which the switch can be firmly clamped to the dashboard 28 of an automobile or to any other equivalent wall or plate. For simplicity in assembling, the front end of the slide 20 may be provided with a T slot 30 adapted to receive the rear end portion 32 of the stem 22 which is separated from the main portion of the stem by a reduced portion 34. A spring element 36 is provided with a leg 38 adapted to project into the slot 30 so as to bear against the end 32 of the stem and to prevent rattling of the end 32 in the slot 30. The other leg 40 of the spring 36 is provided with a lug 42 which snaps over a shoulder (not shown) in a slot 44 in the slide 20 so as to retain the spring 36 in position. The slide 20 is also provided with a transverse bore containing a helical spring 50

under compression, the ends of the spring engaging against a pair of balls 52 within the bore so as to press the balls outwardly against the side walls of the shell 10. These side walls are provided with outwardly dented elements 54 which form shallow recesses on the inner surface of these walls directly opposite the paths of the balls 52 as the slide is moved back and forth within the housing composed of the shell 10 and the base plate 12. Thus the springs 50 and the balls 52 tend to maintain the slide yieldingly in any one of a number of positions defined by the elements 54.

The switch and fuse elements are mounted on 15 the base plate 12, this base plate being preferably made of a suitable insulating material such as a molded artificial resin or an equivalent. A series of rivets 60, 62, 64 and 66 extend through the plate 12, the upper ends of these rivets being flat heads, as indicated in Figures 1 and 6, which constitute stationary switch elements for contact with a movable switch element. The rivets 60, 62, 64 and 66 are arranged in arcuate array, the center of the arc being defined by a small hole 68 which serves as a pivot bearing for a metal lever 70 which has a pivot element 72 inserted loosely in the hole 68. Near the end of the lever 70 opposite the pivot element 72 is a boss 74 which projects toward the base plate and is adapted to 20 contact with the several switch elements 60, 62, 64 and 66. As the lever 70 is rocked about the pivot element 72, the boss 74 slides upon the elements 60, 62, 64 and 66 in succession, thus connecting such elements successively with a conductor 76 mounted on the plate 12. This conductor is preferably provided with an arcuate embossed ridge or bead 78 on which the lever 70 slides so as to provide at all times a good electrical connection between the lever 70 and the conductor 76. The conductor 76 also includes an extension 80, the end of which is electrically connected to a rivet 82 which projects through the plate 12. Near the rivet 82 is another rivet 84 which also projects through the plate 12, these rivets being employed to secure to the plate 12 a pair of metal brackets 86 and 88. Mounted on these brackets, respectively, are a pair of clips 90 and 92 adapted to receive the heads of a cartridge fuse 94. The bracket 88, as indicated in 25 Figure 2, has an end portion 96 which serves as a binding post for the switch. A companion binding post 98 is provided at the end of a conductor 100 which is secured to the plate 12 by a rivet 102 and the rivet 64.

The switch is provided with a pair of resist-

ance elements 106 and 108, the former being connected between the rivets 60 and 62, the latter being connected between the rivets 62 and 64. As the lever 70 is rocked about its pivot, the boss 74 may engage any one of the rivets 60, 62, 64 and 66. Since the rivet 66 is insulated from the other metal parts on the base plate, the switch is open when the boss 74 rests thereon. When the lever 70 is rocked to shift the boss 74 to the rivet 64, a circuit is completed from the binding post 96 through the bracket 88, the fuse 94, the bracket 86, the rivet 82, the extension 80, the conductor 76, the lever 70, the rivet 64, and the conductor 100 to the binding post 98. Thus, when the boss 74 rests on the rivet 64, the resistance coils 106 and 108 are bypassed and the binding posts 96 and 98 are directly connected.

When the lever 70 is swung to bring the boss 74 in contact with the rivet 62, the current which comes from the binding post 96 to the lever 70, as described above, flows through the rivet 62 and the resistance coil 108 to the conductor 100 and the binding post 98. When the boss 74 is moved to contact with the rivet 60, the current which flows from the binding post 96 to the lever 70 continues through the rivet 60, the coils 106 and 108, and the conductor 100 to the binding post 98, this resulting in the cutting-in of both of the resistance coils.

For rocking the lever 70, a pin-and-slot connection between the slide 20 and the lever 70 is provided. As indicated in Figure 6, a plunger 110 is mounted in a suitable recess in the under face of the slide 20, the lower end of the plunger 110 being reduced as at 112 to form a pin riding in a longitudinal slot 114 in the lever 70 between the boss 74 and the portion of the lever that rides on the bead 78. A spring 116 may be seated in the same recess so as to keep the pin 112 within the slot 114 and also to press the lever 70 so that the boss 74 will be pressed against one or another of the rivets so as to make a good electrical contact therewith, and so that the lever 70 will be pressed strongly against the raised bead 78 of the conductor 76. As the slide 20 is moved back and forth in the shell 10, the pin-and-slot connection between the slide and the lever 70 causes the lever to rock about its pivot axis. The recesses 54 by which the slide is yieldingly retained in any one of series of positions are so arranged that such positions of the slide correspond to positions of the boss 74 on the heads of respective rivets 60, 62, 64 and 66. Thus the reciprocal straight-line movement of the stem 22 is converted to rocking movement of the lever 70 about its pivot axis.

It is evident that various modifications and changes may be made in the embodiments of

the invention herein shown and described without departing from the spirit or scope thereof as defined in the following claims.

I claim:

1. An electric switch comprising a rectangular housing consisting of a base plate and a hollow shell with parallel side walls, a conductor pivotally connected adjacent to one of its ends with said base, a plurality of contact elements arranged on said base in the path of movement of the free end of said conductor whereby said elements are successively engaged by said conductor as it swings about its pivot, a slide block fitted between said side walls of the shell for guided movement back and forth, means operatively connecting said block and said conductor, and means for sliding said block to rock said conductor.
2. In an electric switch, a base of insulating material, stationary contact elements thereon arranged in a circular arc, a metal beading mounted on said base and shaped in an arc concentric with the first-mentioned arc, a conductor having a contact element near one end movable into contact successively with said stationary elements and having a pivot element at its other end concentric with said arcs, means engaging said conductor between its ends to press it against said stationary elements and said beading, and means for actuating said engaging means to rock said conductor about its pivot axis.
3. An electric switch comprising a base of insulating material having a recess therein, a plurality of contact elements mounted on said base at equal distances from said recess, a metal ridge on said base adjacent to said recess, a conductor having a turned-down end portion loosely engaging in said recess to act as a pivot, a portion of said conductor slidably engaging said ridge, another portion of said conductor being slidably movable into contact with successive contact elements, and means pressing said conductor against said ridge and said contact elements.
4. In an electric switch, a base of insulating material, a series of contact elements mounted on said base, an elongated metal beading mounted on said base in spaced relation to said series of elements, a conductor movable over said base with one end portion engaging said beading and its other end portion engaging said contact elements in succession, and movable actuating means for shifting said conductor, said means engaging said conductor at a point intermediate the said end portions thereof and resiliently pressing said conductor toward said base.

HUGH W. BATCHELLER.
